(57) **CLAIM**

The ornamental design for a shower curtain ring, as shown and described.

DESCRIPTION

FIG. 1 is a front top perspective view of a shower curtain ring showing our new design;

FIG. 2 is a rear top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines depict portions of the shower curtain ring and a top edge of a shower curtain in which the design is embodied and form no part of the claimed design. The long dash-short dash broken lines illustrate portions of a shower curtain to which the shower curtain ring may be attached that do not form part of the claimed design.
